Charles O. Sherwood
his ATTORNEY.

UNITED STATES PATENT OFFICE.

WALTER J. ASHLEY, OF CHICAGO, ILLINOIS, ASSIGNOR TO ASHLEY MANUFACTURING COMPANY, OF CHICAGO, ILLINOIS, A CORPORATION OF ILLINOIS.

TIRE-PUMP.

1,333,955.

Specification of Letters Patent. Patented Mar. 16, 1920.

Application filed June 26, 1919. Serial No. 307,005.

To all whom it may concern:

Be it known that I, WALTER J. ASHLEY, a citizen of the United States, and a resident of the city of Chicago, county of Cook, and 5 State of Illinois, have invented certain new and useful Improvements in Tire-Pumps, of which the following is declared to be a full, clear, and exact description.

This invention relates to tire pumps and 10 its principal object is to provide a substantial and highly efficient pump of this class. The invention has particular reference to hand operated tire pumps, which ordinarily comprise a plunger, a cylinder 15 and a base or foot plate fastened to the lower end of the cylinder. The usual connections between the cylinder and foot plate are very unsatisfactory and frequently leaks occur at said joint, especially if the pump 20 is handled carelessly or thrown about. With the present invention a leak proof joint is obtained and the danger of loosening the joint by rough usage is reduced to a minimum. The invention consists in the 25 several novel features hereinafter fully set forth and claimed.

The invention is clearly illustrated in the accompanying drawings, in which—

Figure 1 is a vertical cross section of a 30 tire pump embodying a simple form of the present invention; Fig. 2 is a horizontal section taken through the cylinder, the foot plate being partly broken away; Fig. 3 is a plan of an edge expander, forming part of 35 the joint between the cylinder and foot plate, and Fig. 4 is a vertical longitudinal section of a slightly modified form of the pump.

Referring to said drawing, and first to 40 Figs. 1 to 3 inclusive, the reference character 5 designates a fragment of the cylinder and 5 the foot plate of the pump. The plunger and upper part of the cylinder are not shown, but their construction is well known 45 and requires no description so far as this specification is concerned. As is customary, the foot plate 6 extends in both directions from a central hollow boss 7 and preferably an internally threaded boss 8 is cast on the 50 base plate, the interior of which leads to the cylinder 5 through an air passage 9 which opens to the cylinder through a centrally located port 10. An outwardly opening check valve (not shown) may be secured in the 55 threaded boss 8 and the usual flexible air

pipe connection may lead from the check valve.

The inner face 18 of the boss 7 tapers upwardly, and adjacent the bottom 12 said inner face is under cut or formed with a downwardly flaring annular face 11. The cylinder 5 fits tightly against the tapered face 18 and its lower edge portion 13 flares outward and is held in said under-cut portion 11 by an expander 14. Said expander may be in 60 the form of a piece of stamped metal, or it may be cast or otherwise formed, as desired. As shown, said expander is in the form of an inverted cup having a centrally apertured end 19, the aperture 16 forming a port 70 between the cylinder 5 and an air passage 9. From the end 19 extends a flaring side wall 20, the lower edge portion of which flares outwardly as at 15.

To provide said tapering and flaring connection between the boss, cylinder and expander, in assembling the parts, the expander is placed on the bottom of the boss, and the cylinder 5 (unprovided with the flaring end) is forced into the boss with a 80 driving fit. It is forced into the tapered annular space between the tapered faces 18, 20, and the edge portion 13 is forced into the under cut portion, the result being that the end of the cylinder is expanded, taking the 85 shape of the annular groove or space around the expander. Preferably, cement or other sealing material is placed in the groove 17 to provide a supplemental seal for the joint.

Obviously, the flaring connection between 90 the cylinder and foot plate provides a joint which not only is air tight, but one which permanently connects the two pieces, and minimizes the danger of its being loosened in case of rough usage.

In the form seen in Fig. 4 the cylinder and base plate are constructed in all essential respects like the ones shown in Figs. 1 and 2. In place of the separate expander the base plate is formed with an annular flaring groove 100 17^a at the corner formed by the internal face of the boss 7 and bottom 12^a thereof. Said groove may be formed in the foot plate by cutting it therein, or the plate may be cast with the groove. The cylinder and foot 105 plate are assembled by forcing the cylinder into the boss far enough to spread its lower end.

More or less variation of the exact details of construction is possible without departing 110

from the spirit of the invention; I desire, therefore, not to limit myself to the exact form of the construction shown and described, but intend, in the following claims, 5 to point out all of the invention disclosed herein.

I claim as new and desire to secure by Letters Patent:

1. As a new article of manufacture, a tire 10 pump comprising a foot plate having a boss formed with an internal annular under cut portion adjacent the bottom of the boss, a separate edge expanding member having an annular side portion and a flaring edge portion resting upon the bottom of said boss, and a cylinder having an end portion and a 15 flaring edge portion held tightly between the inner wall of the boss and the under cut portion of the boss and the annular side portion 20 and flaring edge of the edge expanding member.

2. A tire pump, comprising a foot plate having a boss formed with an upwardly tapered, internal face and an under cut portion adjacent the bottom, an expander having an upwardly tapered external face and an outwardly flaring lower edge portion, and a cylinder secured between said tapered faces, the edge portion of the cylinder being held in said undercut portion by said flaring edge 25 of the expander.

3. A tire pump, comprising a foot plate having a boss formed with an upwardly tapered internal face and an under cut portion adjacent its bottom, an expander having 30 an apertured end and an upwardly tapered side wall, the lower edge portion of which flares outwardly, and a cylinder secured between said tapered faces, the edge portion of the cylinder being held in said under cut portion by said flaring edge of the expander. 35

WALTER J. ASHLEY.
